UNITED STATES PATENT OFFICE.

GEORGE P. KINGSBURY, OF NEW YORK, N. Y., ASSIGNOR TO MERGENTHALER LINOTYPE COMPANY, A CORPORATION OF NEW YORK.

SLUG-TRIMMING MECHANISM.

Application filed October 4, 1926. Serial No. 139,280.

My invention relates to typographical casting machines, such as linotype machines of the general organization represented in U. S. Letters Patent No. 436,532 to O. Mergenthaler, wherein type bars or slugs are cast in a mold and then ejected therefrom between two trimming knives, which insure the parallelism of their opposite side faces and the exact thickness required. One of these knives is adjustably mounted in order that the distance between the two may be varied at will to accommodate slugs of different thicknesses. More particularly, it relates to a slug trimming mechanism of the type shown and described in the U. S. patent to D. S. Kennedy, No. 1,002,281, wherein the adjustments of the knife are effected against spring tension by means of a rotary sector plate operated by hand and having a series of transverse concentrically arranged screw studs which project different distances from the inner face thereof and which thus determine the extent of the adjustment desired. In the pending application of Samuel Smith, Serial No. 84,059, filed January 27, 1926, means are provided whereby the sector plate or gauge member may be relieved of spring pressure during its rotary adjustment to avoid excessive wear on the parts, although the operator is required to use both hands for effecting each adjustment of the knives.

The present invention is directed to certain improvements in the structure shown in said Smith application and contemplates a simplified arrangement of the parts and one which will enable the knives to be adjusted by the use of one hand instead of two. The exact manner in which this has been accomplished will best be understood from the detailed description to follow.

In the accompanying drawings, I have shown my invention merely in preferred form and by way of example, but obviously many changes and variations may be made therein and in its mode of operation, which will still be comprised within its spirit. Generally speaking, I desire it to be understood that the invention is not limited to any specific form or embodiment, except in so far as such limitations are specified in the claims.

Referring to the drawings:

Fig. 1 is a front elevation of the knife block equipped with the present improvements; 55

Fig. 2 is a horizontal section taken on the line 2—2 of Fig. 1;

Fig. 3 is a vertical section taken on the line 3—3 of Fig. 2; 60

Fig. 4 is a detail perspective view of the front section of the knife block;

Fig. 5 is a perspective view of a knife block showing the improvements in modified form; and 65

Fig. 6 is an enlarged central horizontal section of the knife block shown in Fig. 5.

As best shown in Fig. 2, the adjustable knife A is fastened by screws a to a slide B and arranged opposite to and parallel with the fixed knife A¹. For manufacturing reasons, the slide B is made in two sections B¹, B², and mounted to move horizontally in a supporting frame C bolted rigidly to the main frame of the machine. In its front face, the section B¹ is formed with a pair of superposed horizontal grooves or recesses B³ adapted to accommodate spiral springs B⁴, which bear against integral projections c on the fixed frame C and urge the slide constantly endwise toward the right to move the knife A away from the opposing knife A¹. A rotary sector plate or gauge member D is employed to sustain the knife A in its different adjusted positions, the said member being provided with a series of concentrically disposed screw studs D¹, which project different distances from the inner face thereof and are arranged to selectively engage a hardened stud B⁵ attached to the adjacent end of the slide B. As a result, the knife A is caused to stand in one position or another, according to the particular screw stud in action. 85

The parts so far described, their construction and mode of operation, except as will be hereinafter pointed out, are or may be substantially the same as those presented in the Smith application above mentioned. 90

According to the present invention, unitary means are provided whereby the gauge member is first relieved of the pressure exerted by the springs B⁴, then unlocked, and finally adjusted to any selected position. In the preferred embodiment illustrated, such 100 means consist of a knurled turning knob or

handle E formed with a beveled clutch surface E¹ and which is mounted for axial movement on a horizontal spindle F to make and break connection with the rotary gauge member D. A compression spring E², seated against the knob, serves to maintain the latter resiliently against a retaining screw F¹ on the outer end of the spindle F and normally engaged with a key F², secured to said spindle. The spindle F is journaled in a fulcrum pin D² for the gauge member D and is provided at its inner end with a threaded portion F³ which is arranged in constant engagement with a nut B⁶ projecting from the knife slide B through a slot C¹ in the supporting frame C. The knob E is, in this way, operatively connected to the knife slide and by its rotation will cause the latter to be moved into or out of engagement with the gauge member D. It is desirable that the movement of the knife slide away from the gauge member be limited in order to indicate to the operator when the hardened stud B⁵ stands clear of the longest one of the screw studs D¹. For this reason, the slide B is further provided with a stop pin B⁷ arranged adjacent the nut B⁶ and adapted at such time to contact with the threaded portion F³ of the spindle F to stop the slide in its retracted position.

The device herein employed for locking the gauge member D in its different adjusted positions (see Fig. 2) comprises a plunger G resiliently mounted in a recess C² formed in the supporting frame C and provided with a pair of studs G¹, G², the stud G¹ bearing against one end of a sleeve D⁸ which is loosely mounted on the fulcrum pin D² and connected by a key pin D⁴ to the gauge member D, and the stud G² cooperating with a series of holes or recesses D⁵ disposed around the inner face of the gauge member D. These recesses D⁵ are arranged diametrically opposite to their respective screw studs D¹ so that each will always register with the stud G² when the corresponding screw stud D¹ is brought into operative relation with the hardened stud B⁵ of the knife slide. It will be noted that the plunger G is also provided with a spline G³ which serves to keep the studs G¹, G² properly located at all times. At its outer end, the sleeve D⁸ is formed with a beveled clutch surface D⁶ for engagement with the corresponding clutch surface E¹ of the turning knob E, and is also capable of endwise movement on the fulcrum pin D² to shift the plunger G in unlocking the gauge member.

To aid the operator in adjusting the knife for trimming slugs of different thicknesses and to indicate the adjustments as they are effected, a pointer H is provided which, in the present instance, is fastened to the frame C and arranged flush with the peripheral edge of the rotary gauge member D, the

latter being provided with appropriate marks or graduations D⁷ to be read in connection with the pointer (see Fig. 1).

According to the foregoing arrangement, when it is desired to adjust the knife A, the knob E is turned clockwise until the slide B through the screw F³ and nut B⁶ is moved clear of the gauge member D and stopped in its retracted position by the pin B⁷. The knob is then pushed axially along the spindle F into engagement with the sleeve D⁸ and forces the latter against the frame C. This axial movement of the knob disengages it from the key F² so that it may be turned independently of the spindle F, also shifts the plunger G to withdraw the locking stud G² from the recess D⁵ of the gauge member D, and finally, through the engagement of the clutch surfaces D⁶ and E¹, establishes an operative connection between the knob and the gauge member. The gauge member may now be freely turned about the fulcrum pin D² and set in any selected position with the aid of the graduation marks D⁷ and pointer H. Thereafter, the pressure of the knob is relieved to permit the plunger stud G² to relock the gauge member in its newly adjusted position, and the knob to disengage the sleeve D⁸ and to reengage the key F². The spindle F is then turned by the knob until the hardened stud B⁵ on the knife slide B banks against the selected screw stud D¹ of the gauge member.

Attention is now directed to Figs. 5 and 6, which illustrate an alternative embodiment. In this instance, a face cam F⁴, secured to the inner end of the spindle F and cooperating with a stud B⁸ protruding from the knife slide B, is employed instead of the screw and nut previously described to retract the slide and relieve the sector plate or gauge member D of spring pressure, preparatory to its adjustment. The turning knob E is constantly connected to the spindle by a transverse pin F⁵ and slot F⁶ but is capable of axial movement thereon, as before, to unlock the gauge member D and effect an operative engagement therewith. The locking and unlocking of the gauge member is effected by means of a pin J carried by the gauge member and normally projecting slightly beyond the inner face thereof to engage within one of a series of recesses e concentrically arranged in the supporting frame C and serving in the same capacity as the recesses D⁵ of the first embodiment. The operation of the locking pin J is brought under the control of the knob E by means of a finger E⁴ projecting laterally from the hub of the knob and which is adapted by a partial turn of the latter in a clockwise direction to engage an annular groove J² formed in the head portion of the locking pin. It will also be noted (see Fig. 5) that the gauge member

D is further provided with an auxiliary member D⁸ secured to the outer face thereof adjacent the hub of the knob E. This member is cut away at its lower edge to clear the finger E⁴ as the latter is rocked into and out of engagement with the locking pin J, and is recessed at D⁹ to accommodate both of said parts in their engaged condition. Consequently, when the knob E is pulled outwardly to the position indicated by the broken lines in Fig. 6, the finger E⁴ withdraws the pin J from its locking position and enters the recess D⁹. The knob is thus locked to the auxiliary member D⁸ and an operative connection established with the gauge member D, which may now be freely adjusted by the knob and set in any selected position with the aid of the scale H¹. The knob is then pushed inwardly to restore the pin J to its locking position and given a partial turn in the opposite direction to permit the hardened stud B⁵ of the knife slide to bank against the newly selected screw stud of the gauge member.

25 As a feature of the arrangement last described, it is pointed out that the turning knob E cannot be operatively connected with the gauge member until the knife slide has been retracted and the springs B⁴ compressed. It may also be noted that the pitch of the face cam F⁴ will be determined by the gradually increasing distances the respective screw studs D¹ project from the inner face of the gauge member D, so that in adjusting the sector plate from a high measure, say 40 point, to a lower measure, the cam will continue to retract the knife slide and thus enable its hardened stud B⁵ to clear the longer screw studs D¹. In other words, the initial turn of the knob E, which is limited by the engagement of the finger E⁴ with the locking pin J, is intended only to relieve the sector plate of the pressure exerted by the springs B⁴ and the spaced relation thus established between the stud B⁵ and the respective studs D¹ must be consistently maintained by the cam F⁴ during the adjustment of the sector plate in either direction in order that a corresponding turn of the knob in the opposite direction will suffice to insure the reengagement of the stud B⁵ with the selected screw stud D¹.

Having thus described my invention, its construction and mode of operation, what I claim and desire to secure by Letters Patent of the United States is as follows:

1. In a slug trimming mechanism, the combination of an adjustable gauge member, a knife slide normally engaged therewith, and unitary means for breaking the engagement of the slide with the gauge member and for effecting the adjustment of the latter.

2. In a slug trimming mechanism, the combination of an adjustable gauge mem-

ber, a retractable knife slide resiliently engaged therewith, and a single operating handle serving, by its operation, both to retract the slide and to effect the adjustment of the gauge member.

70

3. In a slug trimming mechanism, the combination of an adjustable gauge member, a retractable knife slide resiliently engaged therewith, an operating handle, and means whereby the latter may be operatively connected and disconnected with and from both of said parts, as and for the purpose described.

4. In a slug trimming mechanism, the combination of a knife slide, an adjustable gauge member, means for locking the latter in its adjusted positions, a spring acting to maintain the knife slide in operative engagement with said gauge member, and unitary means whereby the gauge member may be relieved of the spring pressure of the knife slide, unlocked and then adjusted.

5. In a slug trimming mechanism, the combination of a rotary adjustable gauge member, a retractable knife slide normally engaged therewith, means for locking said member in its adjusted positions, and a turning knob adapted by its rotation to retract the knife slide, said knob being movable axially to unlock the gauge member and effect an operative engagement therewith.

6. In a slug trimming mechanism, the combination of an adjustable gauge member, a retractable knife slide normally engaged therewith, and an operating handle normally connected to the slide for controlling the movements thereof, said handle being movable to break its connection with the slide and to make operative connection with the gauge member.

7. In a slug trimming mechanism, the combination of a rotary adjustable gauge member, a retractable knife slide normally engaged therewith, and a turning knob connected to the slide to control the movements thereof, said knob being movable axially and formed with a clutch member adapted by such axial movement to engage a cooperating clutch member on the gauge member.

8. In a slug trimming mechanism, the combination of a rotary adjustable gauge member, a knife slide resiliently engaged therewith, a turning knob for setting the gauge member in different adjusted positions, and means controlled by the knob for retracting the slide preparatory to the adjustments of the gauge member.

9. In a slug trimming mechanism, the combination of an adjustable gauge member, a retractable knife slide normally engaged therewith, an operating handle for retracting the knife slide preparatory to the adjustment of the gauge member, means whereby the handle may be operatively connected

115

120

125

130

to said gauge member, and locking means to prevent the adjustment of the gauge member, said locking means being arranged to be disengaged by the connection of the handle to the gauge member.

10. In a slug trimming mechanism, the combination of a rotary adjustable gauge member, a retractable knife slide resiliently engaged therewith, a turning knob for setting the gauge member in different adjusted positions, and means operable by a partial turn of the knob relatively to the gauge member for retracting the slide preparatory to the adjustment of said member.

11. In a slug trimming mechanism, the combination of a rotary adjustable gauge member, a turning knob normally discon-

nected from said member, and means controlled by a relative movement of said parts to establish an operative connection between them.

12. In a slug trimming mechanism, the combination of a rotary adjustable gauge member, a pin for locking it in its adjusted positions, a turning knob movable axially into and out of operative engagement with the gauge member, and a member engaging said pin and adapted by the axial movement of the knob to lock and unlock the gauge member as desired.

In testimony whereof, I have affixed my signature hereto.

GEORGE P. KINGSBURY.
